UNITED STATES PATENT OFFICE.

GOELET GALLATIN, OF NEW YORK, N. Y.

DEVICE FOR CUTTING DOVETAILS AND THE LIKE.

1,280,203.

Specification of Letters Patent.

Patented Oct. 1, 1918.

Application filed April 16, 1917. Serial No. 162,342.

To all whom it may concern:

Be it known that I, GOELET GALLATIN, a citizen of the United States, residing at New York city, in the county and State of New York, have invented certain new and useful Improvements in Devices for Cutting Dovetails and the like, of which the following is a specification.

The object of the present invention is to enable dove-tails, miters and the like to be cut mechanically without the necessity of measuring or manually guiding the work.

Figure 1 is a perspective of a device embodying the invention.

Fig. 2 is a vertical section of the same on line 2-2 of Fig. 6.

Fig. 3 is a detail vertical section on line 3-3 of Fig. 8 of the adjustment mechanism.

Fig. 4 is a detail section on line 4-4 of Fig. 3.

Fig. 5 is a plan view of a dial plate.

Fig. 6 is a rear elevation partly in section.

Fig. 6 is a vertical cross section of a fret-saw for use with my invention.

Fig. 7 is a vertical plan of a modification of my invention, and Fig. 7^a is a vertical cross section of this modification.

Fig. 8 is a plan view with the saw carrying part in vertical position.

The essential parts of my invention are a yoke-shaped member provided with an adjustable saw-guide carrier movable and rotatable thereon, the bases of the yoke sliding in the sections of an adjustable vise so that leaving out the movement necessary for gripping the work, there are three movements to bring the saw in mechanically accurate position for dove-tailing, miter-cutting or the like. I have also provided in Figs. 7 and 7^a for a modification in which the yoke is attached directly to the work by means other than the vise arrangements shown in the other figures.

Figs. 1 to 6^a and Fig. 8 show a modification which brings out the three movements which are characteristic of the preferred form of my invention. This preferred form also differs from previous devices of this character in that the yoke has a motion parallel to the vise joining arm. In the ordinary form of vise, the vise joining arm is found underneath the vise arm, and this prevents the cutting of a dove-tail on long pieces of

wood. In my device, a dove-tail can be cut on pieces of wood of any length since the vise joining arm is at the side of the device and not underneath it. Similar symbols are used to denote the various parts in each of the figures. The work is held rigidly by vise sections 1 having jaws 2, and connecting arms 3. The vise section 32 is stationary and integral with the vise arm 3, but the other vise section is free to move in a horizontal direction, being provided with a dove-tail groove 33 in which the free dove-tailed end of the vise arm slides. A long screw 5, manipulated by its handle runs through this free end in the groove of the vise section and when the handle of the screw is manipulated the free end of the vise is brought toward the other end. The work 31 is thus firmly gripped by the jaws of the vise for cutting by the saw after adjustment herein-after explained.

The first movement which the device permits is to bring the saw-guide over the work. The saw-guide is carried by a yoke-shaped member 7, having dove-tailed bases 34, one of which freely slides in the dove-tail groove 6 of one of the vise sections while the other is mounted in a long screw 11 which rests in the dove-tail groove 6 of the other vise section and has a generally horizontal motion in the slot when the handle 12 of the screw 11 is turned. A movement of the handle 12 gives this horizontal motion to the entire yoke and the saw-guide which is carried by it. The function of this portion of the mechanism is therefore to bring the saw-guide over the work.

The second movement permits adjustment to the work so as to make a cut at any angle in any plane of the quadrant at right angles to the yoke; that is to say at horizontal angles to the work. The saw is placed in the guide 20, and held high in the groove 21 with the blade not touching the work, by means of wing-nuts 22. The set screw 18 of the bracket bearing 16 is then turned, releasing the dove-tail gripping portion 15 of the bracket-bearing, part 15 is slid along the dial 14 of the dove-tail projection 13 on the yoke 7 until the angle desired to be cut is obtained, as noted on the dial. Then the set screw 18 is tightened at this point until it presses on the slotted bolt 30 which in turn

presses on the dove-tailed projection 13 of the yoke and holds the bracket-bearing and saw-guide rigidly in position at the desired angle on the quadrant scale. It only remains now to determine the vertical angle of the cut to be mechanically determined and fixed. This is accomplished by rotating hand wheel 17 until the desired angle is obtained and the point on the dial 26 of the bracket-bearing registers with the point on the rim-dial 8 of the yoke. The dial 26 is provided with a key-way pin 29 which couples the dial with shaft of bolt 28 and prevents any shifting of the dial. In order to prevent the set-screw from forcing the slotted bolt 30 against the projection of the long screw 28 a spring 27 is placed in the aperture as shown.

The saw 24 is released by revolving the wing-nuts and falls into the contracted portions 23. The saw then registers the required angle with work 31 and this angle can be maintained for any depth required. In the same way the device can be adjusted to cut exactly similar angles on the opposite side of the work. By means of this invention we can make cuts at angles to the vertical or horizontal by mechanical means with absolute accuracy. The sections of the vise 30 are screwed together by means of screws 4.

It will be observed that for dove-tails of conventional cut, one fastening or the other will be kept at 0° . For instance, in cuts where the vertical cross sections throughout the dove-tail are identical, the bolt 17 is permanently fastened at 0° on the small dial 26, so that the plane of the saw is always at right angles to the yoke. In the other usual form where the vertical cross section of the cut diminishes toward the back thereof, the screw 18 permanently fastens the saw-guide on the yoke at 0° , but the saw-guide is free to move in vertical angles.

My device is also adapted to sever the dove-tails from the wood. In dove-tails of the male class, the operation is simply to turn the wood on its side bringing the line to be severed under the blade of the conventional saw with the dials at 0° . When the dove-tails are of the female class I may employ a fret-saw having a holding portion of rigid material as shown in Fig. 6^a. The fret-saw 40 is mounted on two arms 41 by means of pins 42, which arms are fastened or integral with a rigid back or holding portion 43, and a handle 44. The method of operation is to fasten the holding portion 43 of the saw to the saw guide with the dials at 0° . The saw blade 40 is of such narrow width that it will easily slip into the grooves of the cut dove-tail even at right angles to the grooves. The fret-saw is slipped through and along the dove-tail grooves cut in the wood until the wood is in a position generally parallel with the vise arms and

the saw is in a position to give a vertical cut through that portion of the wood which holds the dove-tail to the main body of the wood. The saw is then operated until the dove-tail is sawed through and separated 70 from the wood. It will be observed that the space between the saw blade 40 and the holding portion 43 must be large enough to permit the passage of that portion of the wood which lies between the dove-tail and the edge 75 of the wood, as this is the position of that portion while the dove-tail is being severed. A space of from 3 to 4 inches will usually be found sufficient.

A special construction is shown in Figs. 7 and 7^a by which wide boards can have a series of dove-tails sawed thereon. In Figs. 1, 2 and 6, the dove-tail bases 9 of the yoke-shaped quadrant are shown to be fastened in dove-tail grooves 34, by means of screws 35, and the grooves 34 have dove-tailed bases so as to fit in the dove tail grooves 6 of the vise sections. The object of this special construction is to enable the entire yoke and the saw-carrier to be lifted out of the vise and fitted into a reinforcing yoke 36, for the special work above set forth. In Figs. 7 and 7^a the yoke and carrier are indicated and the arms of the lower fastening yoke 36 are fitted with a ledge 38, having dove-tail 95 grooves so that the bases 9 of the quadrant yoke can be fastened therein by screws 37. The dove-tails are marked off on the work 39 which is placed between the work bench and the device, the ledges of the lower yoke 100 resting on the work thus firmly holding it in position.

The device can be made so that the yoke cannot be removed from the vise sections and in that event parts 9 and 34 in Fig. 1 105 are in one piece and pin 35 not required.

The device has a wide range of work and is adapted to make cuts at angles to the vertical or horizontal in wood or metal and turn out mechanically perfect moldings, drawer 110 parts or any wood or metal part where such angular cuts are required. Dove-tails can be formed on boards of any length owing to the position of the vise arm.

Having described my invention, what I 115 claim is:

1. A device of the character described comprising: slidably connected supporting members having work-holding jaws, a rigid arc shaped member whose free bases straddle the jaws and are slidably carried in the supporting members to admit of adjustment of the latter and of its own adjustment with respect to the latter, and a saw guide adjustable in planes at right angles to each 120 other carried by said arc shaped member.

2. A device of the character described comprising: two supporting members having work-holding jaws, a joining member carried by one of said supporting members, 125

straight line adjustable connecting means between said joining member and the other of said supporting members, a rigid arc shaped member whose free bases straddle the 5 jaws and are slidably carried in the supporting members, means connected to that supporting member which carries the joining

member for slidably adjusting the arc shaped member in a line parallel to the adjustment of the supporting members, and a 10 saw guide adjustable in planes at right angles to each other carried by said arc shaped member.

GOELET GALLATIN.
